J. D. HEWITT.
COAL RECEPTACLE.
APPLICATION FILED AUG. 15, 1916.

1,220,422.

Patented Mar. 27, 1917.

UNITED STATES PATENT OFFICE.

JOSEPH D. HEWITT, OF PATERSON, NEW JERSEY, ASSIGNEE OF ONE-HALF TO LLOYD D. HENDERSON, OF RIDGEWOOD, NEW JERSEY.

COAL-RECEPACLE.

1,220,422.

Specification of Letters Patent. Patented Mar. 27, 1917.

Application filed August 15, 1916. Serial No. 115,005.

To all whom it may concern:

Be it known that I, JOSEPH D. HEWITT, a citizen of the United States, residing at Paterson, in the county of Passaic and State 5 of New Jersey, have invented certain new and useful Improvements in Coal-Receptacles, of which the following is a specification.

The object of this invention is to provide 10 a receptacle in which coal may be kept in ample quantity in convenient reach of a stove or range and from which the coal may be removed with facility and without spilling it about so long as ordinary care in re- 15 moving it from the receptacle to the fire is used, the same to be strong, durable, simple and inexpensive in construction and preferably adapted to be moved about the floor without the necessity of lifting or sliding 20 it thereover. While the receptacle has been designed especially to receive coal, it may be employed for receiving other materials.

In the accompanying drawings, Figure 1 is a vertical sectional view of the recepta- 25 cle;

Fig. 2 is a horizontal sectional view of the same;

Fig. 3 is a fragmentary front elevation, showing the lower portion thereof;

Fig. 4 is a top plan view of the cover;

Fig. 5 is a fragmentary plan of the false bottom;

Fig. 6 is a front elevation of a strut to support the latter; and

Fig. 7 is a sectional view showing the manner of forming the bottom seam and connecting the spout to the side wall of the receptacle.

The receptacle includes a bottom wall *a*, 40 a cylindrical side or body wall *b*, which is preferably connected with said bottom wall by a so-called lock-seam *c*, and a cover *d*, having a handle *e* and a flange *f* which fits into the upper end of the receptacle body.

An opening *g* is cut in the wall *b*, preferably rectangular in shape, and into this is 45 snugly fitted the spout shown in Figs. 1 and 2. This consists of a piece of sheet metal bent to form a flat bottom *h* and two side 50 walls *i*. Each side wall is extended at its inner end as a lip *i'* and is turned outwardly, being curved to the same radius as the wall *b* of the receptacle; each such lip is secured flat against the inside face of the wall *b* in 55 some substantial manner, as by the rivets *j*.

The bottom wall *h* of the spout, which is preferably turned up somewhat at the front, has its inner edge formed into a lock seam with the edge portion of the material of the wall *b* at the lower side of opening *g*; 60 that is to say, said edge of the bottom wall *h* of the spout is bent down and then relatively outward back upon itself to produce the fold *k* and said lower edge of opening *g* is bent inwardly upon itself to produce the 65 fold *l*, the two folds *k* *l* being hooked into each other and pressed or hammered flat. This construction, involving the spout being supported in a substantial manner around three sides of the opening *g*, makes 70 the spout well able to resist the wear and tear incident to its service and displacement due to accidental blows or pressure.

An inclined wall *m*, forming a false bottom, is arranged just above the spout. This 75 wall inclines rearwardly and downwardly, extending close to the wall *b* at all points except at the back, where is left the space or opening *o*. Said wall is formed from a part-circular piece of sheet material having tabs *p* at its circular edge (Fig. 5) bent up and secured by rivets *q* (Fig. 1) to the inner face of wall *b*. To reinforce the back edge of the wall, which is straight, a strut *r* having its ends bent down and riveted to wall *b* of the receptacle, is arranged 80 to underlie said back edge. The coal, placed in the receptacle, falls toward and through the opening *o*, leaving only a small quantity, as at *s*, lodged at the back on the bottom *a*, 85 where it can be conveniently reached and removed by a shovel entered at the opening *g*.

For supporting the receptacle I prefer- 90 ably provide several legs *t* and a horizontal 95 hoop *u* of somewhat greater diameter than that of the body wall *b* of the receptacle, riveting the legs to said wall and the hoop to the legs. The base thus provided makes it possible to roll the receptacle about the 100 floor, instead of sliding or lifting it.

In the cover may be provided a hole *v* by means of which, without removing the cover, the user can see whether or not the receptacle requires re-filling. The receptacle may 105 also be used for the burning of refuse, in which case such hole serves as the draft outlet, the opening *g* being then the draft inlet. *w* is a cover for said hole, pivoted to the cover *d* under the handle *e* in such man- 110

ner that its movement is limited by the handle.

Except for the handle *e*, strut *r*, the legs and the hoop, which are all preferably formed of strap iron, the material of the receptacle is sheet iron.

Having thus fully described my invention, what I claim and desire to secure by Letters Patent is:

- 10 1. A receptacle for coal and similar materials consisting of an upright hollow body having a bottom and an outlet in one side thereof above the bottom and serving for the withdrawal of the material, and a spout 15 projecting from the body at said outlet and having a bottom and two side walls, said body and spout being formed of sheet metal

and the side walls of the spout being extended into said outlet and forming lips and said lips being secured flat against said body 20 both sides of the outlet.

2. A receptacle for coal and similar materials consisting of an upright hollow body having a bottom and an outlet in one side thereof above the bottom and serving for 25 the withdrawal of the material, and a spout projecting from said body at said outlet and having a bottom and two side walls, said body and spout being formed of sheet metal and the side walls of the spout being secured 30 to said body and its bottom wall joined in a lock-seam with said body.

In testimony whereof I affix my signature.

JOSEPH D. HEWITT.
